CLAIM

The ornamental design for a faucet, as shown and described.

DESCRIPTION

FIG. 1 is a top front perspective view of a faucet showing our new design;

FIG. 2 is a top rear perspective view thereof;

FIG. 3 is a top plan view thereof;

FIG. 4 is a front elevational view thereof;

FIG. 5 is a left side elevational view thereof;

FIG. 6 is a right side elevational view thereof;

FIG. 7 is a rear elevational view thereof; and,

FIG. 8 is a cross-sectional view of the spout of the faucet taken along line 8—8 in FIG. 1.

The broken line showing of an aerator in FIG. 1 is for purposes of illustration only and forms no part of the claimed design.
